Primary Examiner — Karen E. Eldridge Powers*Assistant Examiner* — Kimberly Barnes(74) *Attorney, Agent, or Firm* — Sheridan Ross PC(57) **CLAIM**

The ornamental design for headgear, as shown and described.

DESCRIPTION

FIG. 1 is a left side perspective view of the headgear showing the new design;

FIG. 2 is a lower front perspective view thereof;

FIG. 3 is a rear elevation view thereof;

FIG. 4 is a right side elevation view thereof;

FIG. 5 is a left side elevation view thereof;

FIG. 6 is a rearward top perspective view thereof;

FIG. 7 is a bottom plan view thereof; and,

FIG. 8 is an exploded front elevation view of the headgear in an unassembled state.

The broken lines shown in the drawings illustrate fold lines which form part of the claimed design.

1 Claim, 8 Drawing Sheets(56)
